UNITED STATES PATENT OFFICE.

SIMON CLARK, OF WINSTON, MISSOURI.

CHURN.

SPECIFICATION forming part of Letters Patent No. 436,213, dated September 9, 1890.

Application filed April 23, 1890. Serial No. 349,084. (No model.)

To all whom it may concern:

Be it known that I, SIMON CLARK, a citizen of the United States, residing at Winston, in the county of Daviess and State of Missouri, 5 have invented new and useful Improvements in Churns, of which the following is a specification.

This invention relates to that type of churns having a swinging dasher comprising horizontal beaters, which are substantially triangular in cross-section.

The object of my invention is to improve the prior dasher by providing a novel construction, whereby the flow of the cream 15 through the dasher at the ends of the beaters is facilitated.

The invention consists in a churn-dasher comprising horizontal beaters of substantially triangular form, having openings between 20 them for the passage of the cream, and side bars carrying the beaters and having beveling, diverging cut edges arranged at and rising above the ends of the beaters to facilitate the flow of the cream through the dasher at such 25 beveled parts.

In the accompanying drawings, Figure 1 is a central vertical section of a churn embodying my invention, the lid being removed. Fig. 2 is a transverse vertical section, the 30 dasher being in elevation. Fig. 3 is a view of the lid.

In the said drawings, the reference-numeral 1 denotes the body of the churn, which is of any desired capacity, from four to eight 35 gallons being that usually employed. Viewed in side elevation the churn-body has substantially the form of a segment of circle, the segment being truncated at its upper and smaller end. This body is mounted upon legs 2. Its 40 bottom 3 is preferably composed of a sheet of galvanized iron, zinc, or other suitable metal; but it may be also provided with an interior lining of galvanized iron to secure perfect cleanliness. A vertical flange 4 surrounds and rises above the rectangular open 45 mouth.

The reference-numeral 6 designates the churn-dasher, which is composed of a rectangular plate of wood of such width as to 50 substantially span the interior space of the churn. The dasher is provided with a series of transverse beaters 7, of substantially tri-

angular form in cross-section, the base of said rectangle being arranged at right angles with the parallel side pieces 8 of the dasher, while 55 the apex lies in the central line of such side pieces. Between the apex of each beater and the base of the one next above a sufficient space is allowed to admit of the passage of the cream. At the ends of the beaters are 60 formed beveling cuts 9, extending from the base of one beater to that of the next above and entering the side strips 8 at an outwardly-diverging angle, whereby at each stroke in either direction certain portions of the cream 65 are, by means of these beveling faces, forced laterally inward or toward the center of the dasher, and caused to pass through the same between the beaters.

United with the dasher is the lever by 70 which it is operated, consisting of two parallel bars 9^a, of metal or other material, which pass through longitudinal openings in the side pieces 8, and protrude at the lower ends of said pieces, their ends receiving washers 75 or nuts 10. After emerging from the upper ends of the side pieces 8, the bars 9^a slightly diverge, and are then bent sharply outward, forming journals 12, which rest in seats 13, formed centrally and transversely in the edges 80 of the side pieces.

In order to prevent rapid wear, journal-blocks 14 will usually be inserted in recesses formed in the opposite side walls of the churn, said blocks being formed of any suitable hard wood.

The journals 12 are of such length as to pass into two triangular recesses 15, formed in the flange 4, which surrounds the open mouth of the churn, and at their outer ends 90 the bars are bent vertically upward and extended to a suitable point above the top of the churn, where their ends are united to a connecting cross-bar 16.

The journals 12 are retained in the seats 13 95 by means of latches 17, pivoted upon the flat upper edges of the walls of the churn and adapted to swing over and hold the journals in place.

The mouth of the churn is closed by a removable lid formed in two parts 18 and 19, the former portion being of such size that it will enter and substantially fit the open mouth of the churn, angular recesses 20 being formed

in the edges of the part 18 to receive the inner ends of the journals 12 and permit the swing of the lever.

The part 19 is united to the part 18 in such manner as to form a projecting edge or flange 21, which is received within the flange 4 and rests upon the open top of the churn. Recesses 22 are formed in the lower faces of the projecting edge 21 to accommodate the latches 17.

It will readily be seen that by this construction of cover or lid the escape of the cream will be rendered practically impossible, while the parts are very simple in form, readily removed and replaced, and quickly and easily cleaned.

What I claim is—

In a churn, a dasher consisting of a series of horizontal beaters of substantially triangular form, having openings between said beaters for the passage of the cream, the side bars by which said beaters are carried having beveled diverging cut edges 9, arranged at and rising above the ends of the respective beaters to facilitate the flow of the cream through the dasher at such beveled parts, substantially as described.

In testimony whereof I have affixed my signature in presence of two witnesses.

SIMON CLARK.
